UNITED STATES PATENT OFFICE.

WILLIAM LATHROPE WRIGHT, OF KANSAS CITY, MISSOURI, ASSIGNOR OF ONE-HALF
TO WILLIAM WALTER EAKMAN, OF MISSOURI VALLEY, IOWA.

WINDOW SCREEN.

Application filed February 12, 1923. Serial No. 618,497.

To all whom it may concern:

Be it known that I, WILLIAM LATHROPE WRIGHT, a citizen of the United States, residing at Kansas City, in the county of Jackson and State of Missouri, have invented certain new and useful Improvements in Window Screens, of which the following is a specification.

My invention relates to an all-metal window screen and one object is to provide a durable frame for screens of this character which is fireproof and will outlast the ordinary wooden frame usually employed in the construction of window screens.

15 A further object is to provide a screen frame which may be readily adjusted to fit window frames of different widths and lengths and can be quickly installed for use, or removed when it is desired to wash 20 the windows.

Another object is to provide a frame of such cross sectional configuration and provided with retaining elements whereby the wire screen can be drawn taut and firmly held in place, or quickly removed when worn out and replaced by another.

Other objects will hereinafter appear, and in order that the invention may be fully understood, reference will now be had to the 30 accompanying drawing, in which:

Fig. 1 is a broken front elevation of a window with the screen in position therein.

Fig. 2 is an enlarged detail perspective view of one of the elbows and a portion 35 of one of the strips which connect said elbows.

Fig. 3 is a detail perspective view of a retaining strip, a plurality of which are employed in holding the wire screen in the 40 frame.

Fig. 4 is an enlarged cross section of the frame and the screen on line IV of Fig. 1.

Fig. 5 is a fragmentary side elevation of 45 the screen frame in position in the window frame.

Referring now in detail to the various parts, A designates the window frame, B the upper window sash, and C the vertical stops which coact with other stops usually employed in holding the upper sash B in place in the frame A.

Referring now more particularly to the screen frame constituting an important feature of the invention, 2, designates a plurality 50 of sheet metal elbows, one of which is

employed at each corner of the frame as disclosed by Fig. 1. The intermediate front portion 4 of each elbow 2 projects outwardly and has an abrupt longitudinal portion 6 and an oblique angular longitudinal portion 8, which reinforce the elbow and assist in firmly holding the wire screen 30 in position as will hereinafter appear. The longitudinal margins 10 of the elbows 2 turn inwardly towards each other to assist in holding side and end sheet metal strips 12 and 14 in assembled relation with said elbows.

The strips 12 and 14 are of substantially the same cross sectional configuration as the elbows 2, excepting that their margins 16 are not turned toward each other like the margins 10. The strips 12 and 14 slidably engage the elbows 2, so that the frame may be adjusted longitudinally and transversely to fit window frames of different lengths 75 and widths. After being adjusted in the elbows 2, the strips 12 and 14 are firmly locked in position by bolts 18 and 20 extending through holes 22 in the elbows and longitudinal slots 24 and 26 in the strips 12 80 and 14, respectively.

28 designates retaining strips one of which is associated with each strip 12 and 14. The retaining strips 28 are of substantially the same cross sectional configuration as the strips 12 and 14 in order to snugly fit therein and firmly hold the wire screen 30 in place as shown more clearly by Fig. 4. Each retaining strip 28 is provided near its ends with longitudinal slots 32, to register with the slots 24 or 26, so that the bolts 18 and 20 may be placed through said slots to hold the several parts together.

The two uppermost elbows 2 of the frame are provided with pivots 24 adapted to detachably engage brackets 36 secured to the adjacent sides of the window frame as shown more clearly by Fig. 1. The brackets 36 have downwardly and rearwardly extending slots 38 to receive and carry the pivots 34 95 backwardly, so that they in turn will hold the metal frame against the stops C. When the window panes E are to be washed the metal frame carrying the screen 30 may be swung outwardly and propt in open position to gain access to said panes, or said frame may be entirely removed by disengaging the pivots 34 from the brackets 36, as preferred.

In assembling the screen frame the strips 12 and 14 are slipped into the respective 110

- legs of the elbows 2 and are adjusted longitudinally until said frame fits the window frame A. The wire screen 30 is then laid across the back of the screen frame, after which the retaining strips 28 are placed against the back of the screen 30 and pressure is applied to force the same into the intermediate front portions 4 of the elbows and the corresponding portions of the strips 12 and 14. This operation draws the screen 30 taut after which the retaining strips 28 are secured in place by the bolts 18 and 20, which also firmly secure the strips 12 and 14 in the elbows 2.
- 15 While in the drawing I have only shown the screen frame covering the lower half of the window frame A, it is to be understood that said screen frame may be made in longer sizes to cover the entire opening in 20 the window frame A. I also reserve the

right to make such changes in the construction, combination and arrangement of parts as properly fall within the spirit and scope of the appended claim.

Having thus described my invention, what I claim and desire to secure by Letters Patent, is:

A frame consisting of elbows having in-turned margins and outwardly projecting intermediate portions, side and end strips 30 capable of longitudinal adjustment in said elbows but held from lateral displacement by said in-turned margins, and retaining strips similar in cross section to the side and end strips and adapted to hold a screen in 35 said frame.

In testimony whereof I affix my signature.

WILLIAM LATHROPE WRIGHT.
